CHARLES SPRING, OF HYDE PARK, AND ANDREW SPRING, OF WESTON, MASSACHUSETTS.

Letters Patent No. 90,034, dated May 11, 1869.

IMPROVED VELOCIPEDÉ.

The Schedule referred to in these Letters Patent and making part of the same.

To all whom it may concern:

Be it known that we, CHARLES SPRING, of Hyde Park, Norfolk county, and ANDREW SPRING, of Weston, Middlesex county, all in the State of Massachusetts, have invented Improvements in Velocipedes; and we do hereby declare that the following, taken in connection with the drawings which accompany and form part of this specification, is a description of our invention sufficient to enable those skilled in the art to practise it.

The new mania for riding velocipedes has developed almost numberless changes and improvements upon the old form of "three-wheelers" and the French "two-wheelers."

Our improvement consists in the employment as rear wheels of two drag or follower-wheels, the axle of each of which is hung in bearings placed out of vertical line with the vertical shaft by which the bearing-frame is pivoted to the carriage, so that when the leader-wheel is turned in either direction by the rider, (to change the course of the vehicle,) by means of a vertical axis in vertical line with the centre of the wheel, each follower-wheel is self-adjusting in the same direction, and in certain details hereinafter stated.

The drawings represent a velocipede embodying our improvements.

A shows a side elevation of the vehicle.

B is a front view of it.

C, a plan of it.

D, a vertical section through the brake-mechanism.

a denotes the perch;

b, the saddle-bar;

c, the leader-wheel;

d, the follower-wheels.

The wheel c is fixed upon an axle, e, supported in bearings, f, at the foot of vertical bars, g, which project from a boss, h, over the wheels, from which boss rises the vertical shaft i, which, passing through a quill or vertical bearing, k, has at its top two arms, l, which support handles, m, by means of which the vertical axis of the wheel may be turned to turn the course of the machine.

At each end of the axle e is a crank, n, upon which is supported a stirrup-frame, o, which carries a series of swivelling foot-pieces, p, upon either of which the foot of the rider may bear in propelling the vehicle.

Each stirrup-frame or bar, o, is jointed at top to a crank, q, of a crank-shaft, r, running through the vertical shaft i, each crank, q, being in position to be grasped by the hand of the rider, so that the hands, as well as the feet, may be made use of to turn the driver or propelling-wheel c, each crank, q, being preferably provided with a loose sleeve for the grasp of the hand.

Passing down through the shaft i is a rod, t, at the foot of which is a brake, u. The rod is raised and depressed by an eccentric, v, fixed on the shaft w, which carries the handles m, the eccentric acting upon a slotted piece, x, at the top of the rod, and enabling the rider, by a turn of the hand-grasps m, to instantly stop the wheel.

The top of the wheel under the perch is covered by a shield, z, which extends partially around the wheel, and has a flange, y, projecting over the side of the wheel, adjacent to the periphery. This shield is for

the purpose of protecting the clothes of the rider from contact with that part of the edge of the wheel near which the legs come.

The rear end of the perch rests upon the cross-bar a², in the opposite ends of which are journalled the short shaft b² of the bearing-frames c², in which are journalled the axles d², upon which are fixed the two trailing-wheels d.

Each bearing-frame is so formed that the axis upon or with which its wheel rotates is not in a vertical line with the axis or shaft upon which the bearing-frame turns, the effect of which is to cause the wheel to readily turn as the leader-wheel turns, thereby saving the wheel from strain and rendering it easier to propel the velocipede.

Upon each shaft, b², is fixed a wheel or disk-plate, f², between whose top surface and a plate, g², fixed to the cross-bar a², are friction or turn-table rolls, h², whose gudgeons turn in bearing-pieces, i², projecting from the plates g².

Each plate, f², bears against the rolls, and as the trailing-wheels turn in changing their direction, the stress comes upon the plates f² g², and not upon the short shafts b², the trailing-wheels also rotating with much less friction than if the rolls were not employed, and being kept steady in their movements.

Both follower-wheels incline to turn in the same direction in changing the course of the vehicle, but as either one may meet obstructions, we connect the two wheels f², so that the turning of one gives motion to the other. As the wheels will not rotate equally, however, in turning short curves, this connection is not made positive.

The connection shown is made by a band, k², running around the two wheels, in a groove in each, instead of which the two pulley-wheels f² may be made of greater diameter, and a horizontal wheel play between them on a shaft projecting from the bar a², this mid-wheel having an elastic periphery that shall press against each wheel, f², to turn it or be turned by it.

A velocipede thus made has material advantages over any of those now in use, not only on account of the greater ease with which it may be propelled, but also by reason of the facility with which its direction may be changed, either in reversing its movements or in turning.

We claim—

1. In combination with the leader-wheel, the two follower or trailing-wheels, the axis of each of which is hung in bearings placed out of vertical line with the shaft by which the wheel-frame is connected to the carriage-frame.

2. Also, in combination with each follower-wheel, the plates f² g² and friction-rolls h², substantially as shown and described.

3. Also, follower or trailing-wheels, arranged as described, and connected by a band or equivalent mechanism, substantially as described.

CHARLES SPRING.

ANDREW SPRING.
